UNITED STATES PATENT OFFICE.

JOHN A. CASEY, OF ST. PAUL, MINNESOTA.

ANTIFRICTION-TRANSFER FOR SHOES.

1,334,991.

Specification of Letters Patent. Patented Mar. 30, 1920.

Application filed June 18, 1919. Serial No. 305,120.

To all whom it may concern:

Be it known that I, JOHN A. CASEY, a citizen of the United States, residing at St. Paul, in the county of Ramsey and State 5 of Minnesota, have invented new and useful Improvements in Antifriction-Transfers for Shoes, of which the following is a specification.

My invention relates to an improved article of manufacture which is adapted by the application of heat and pressure to attach an antifriction surface to the inner surface of the heel of a shoe, boot or slipper. It is well known that the linings in the 15 backs of shoes and other footwear and the heel portions of hose wear quickly, due to the rubbing action and friction occurring when shoes are worn, and it is the primary object of this invention to reduce this wear 20 to a minimum and prevent rubbing and chafing of the skin of the heel portion of the foot, in a simple and inexpensive manner. To this end, my invention is a new article of manufacture consisting of a strip 25 or plate of cotton flannel or other suitable material forming a base element coated with a suitable antifriction transfer material such as paraffin or other suitable material which at normal temperature remains solid but 30 which, by the application of suitable heat and pressure against the base when the article of manufacture is placed in the shoe against the heel surface to be treated, will melt and transfer the antifriction material 35 to and coat said surface, after which the base is removed leaving the antifriction material deposited in solidified condition upon the treated surface.

In the accompanying drawing forming 40 part of this specification Figure 1 is a plan of my improved transfer, and Fig. 2 is a side elevation of a detail portion of a shoe, partly broken away and in section, showing my improved transfer in position against 45 the heel surface in a shoe in readiness to apply the antifriction material when heat and pressure are applied.

My improved transfer base A is suitably shaped to be adjusted against the inner surface 50 of the heel of a shoe over its lined portion which ordinarily is subjected to most of the wear, due to the movement of the heel of the foot in the shoe. This base member has substantially a straight lower edge 2 and a curved upper edge 3, although this

shape may be variously modified to conform more particularly to the portion in the shoe which it is desired to treat with the antifriction material. This plate or base is coated or saturated with paraffin either by brushing 60 molten paraffin over its surface and cooling or by soaking the base in the molten paraffin after which it is allowed to solidify. It is preferable to coat only one side of the base A although as stated the entire device 65 can be saturated with the paraffin. In Fig. 2 of the drawing the coated side 4 is shown placed against the lining 5 of the back of the heel 6 of the shoe and 7 indicates the 70 wall of the base A.

When it is desired to treat a worn surface in a shoe such as B with the antifriction material the base element is placed over the surface to be treated such as the heel portion 6, with its paraffin coated side 4 resting against said surface, after which a hot iron is rubbed over the inner surface of the base until the paraffin is melted, whereupon, due to the pressure exerted by the iron against the base, the paraffin is transferred 80 onto the surface of the lining in the shoe which is treated. After the hot iron has been removed the base is stripped and removed from the shoe leaving the solidified paraffin coated over the lining or worn surface in the shoe. This coating being of antifriction material serves to reduce wear and 85 friction of the heels of hose and chafing of the skin of the foot, and it also serves to seal and hold the frayed edges of holes in 90 the lining on the leather inner surface of the shoe, when the lining is worn.

While I have specified cotton flannel as suitable material out of which to construct the base it will be understood that other 95 flexible materials may be employed for that purpose; also that instead of using paraffin wax, any other suitable antifriction adhesive material may be employed which can be transferred from the base onto the inner surface of the shoe by the application of heat and pressure, within the spirit of my invention.

The materials mentioned permit of placing the base elements coated with paraffin 105 in envelopes convenient for distribution and the low cost of production lends greatly to the filling of a long felt want for quickly and conveniently treating linings in shoes and of repairing worn inner surfaces by 110

the users without having to employ shoe cobblers at increased expense and loss of time.

Having described my invention, what I claim as new and desire to secure by Letters Patent is:

1. An improved article of manufacture consisting of a flexible base shaped to cover the inner heel surface of a shoe to be treated and coated with an adhesive antifriction transfer medium on its surface to be applied to said heel surface.

2. A transfer for shoes consisting of a flexible base shaped to conform with the inner surface of the shoe to be treated, said base being coated with an antifriction trans-

fer medium on the side lying adjacent to said surface, said transfer medium being adapted to be melted by the application of heat to the inner surface of said base.

20

3. A transfer for shoes consisting of a cloth base approximating the size and shape of the surface to be treated in the shoe, said base being impregnated with paraffin and adapted by the application of heat and pressure to its inner surface while in the shoe to coat the melted paraffin on said surface.

25

Signed at St. Paul, in the county of Ramsey and State of Minnesota, this 9th day of June, 1919.

JOHN A. CASEY.
